UNITED STATES PATENT OFFICE.

JOHN W. CAVANAGH, OF NEW YORK, N. Y., ASSIGNOR TO MARY E. GUGEL, OF OAKHURST, NEW JERSEY.

REVERSING MECHANISM FOR ELECTRICALLY-OPERATED WASHING-MACHINES.

1,208,746.

Specification of Letters Patent.

Patented Dec. 19, 1916.

Application filed October 27, 1914. Serial No. 868,800.

To all whom it may concern:

Be it known that I, JOHN W. CAVANAGH, a citizen of the United States, residing at the city of New York, borough of Manhattan, county and State of New York, have invented a certain new and useful Reversing Mechanism for Electrically-Operated Washing-Machines, of which the following is a specification.

10 This invention is a reversing mechanism especially adapted for use in connection with a rotatable cylinder of a washing machine intended to be operated by a suitable motor, preferably by an electric motor, the armature of which rotates in one direction continuously.

The invention embodies a load carrier in the form of a cylinder mounted for rotative movement, a motor of the kind specified, and 20 an automatic reversing gear whereby rotation is imparted to the load-carrying cylinder first in one direction and then in a reverse direction.

Owing to the momentum acquired by the 25 cylinder, particularly should it be loaded heavily, there is a tendency on the part of certain elements composing the reversing gear to become wedged fast one to the other at the period of shifting from one direction 30 to the other, as a result of which an excessive load is thrown on the motor and the latter is liable to burn out. To prevent this condition, I employ yielding connecting means in the engaging parts of the reversing gear; 35 as will be hereinafter fully explained.

Other features and advantages of the invention will be apparent from the following detailed description.

In the drawings, Figure 1 is a sectional view through the load-carrying washing cylinder and a tub within which said cylinder is positioned, the motor-driven mechanism being shown in elevation. Fig. 2 is a cross section through the tub on the line 45 2-2 of Fig. 1, the cylinder being illustrated in dotted lines. Fig. 3 is a plan view of a part of the cylinder and a part of the tub illustrating one of the saddles and hangers for supporting an end portion of the cylinder shaft. Fig. 4 is a horizontal sectional plan view of the driving and reversing mechanism, the plane of the section being indicated by the dotted line 4-4 of Fig. 5. Fig. 5 is an elevation of the automatic reversing mechanism for imparting the oscil- 55

lating motion to the washing cylinder. Fig. 6 is a cross section on the line 6-6 of Fig. 4. Fig. 7 is a detail sectional view through the shifting clutch member. Fig. 8 is a detail view showing an extension hub for one end 60 of the cylinder.

A designates a load-carrier to which rotative movement, first in one direction and then in an opposite direction, is adapted to be applied by the agency of a motor and a 65 train of reversing gears, the latter being operated automatically. Said load-carrier is shown as a washing cylinder of suitable dimensions and material. The cylinder A is provided with perforations *a* for the free 70 flow of water through it as said cylinder rotates within a receptacle, the latter being shown in the drawings as a stationary wash tub B. This wash tub is of any suitable form now installed as a plumbing appliance 75 in buildings, apartments and other places, some of which tubs are composed of enameled iron. The cylinder is provided with a movable cover section *a'* to enable access to be obtained to the chamber of said cylinder for the purpose of placing the clothes therein or removing them therefrom. As shown, the cylinder is provided with an axial shaft C, the end portions of which extend beyond the respective cylinder heads, 80 whereby said shaft C is adapted to be supported in suitable openings *d* constituting shaft bearings in the hangers D D'. Said hangers are positioned within the tub near 85 opposite side walls thereof, but the hangers 90 are not in contact with the walls of the tub, the lower ends of the hangers terminating a suitable distance above the bottom of the tub. The hangers are, or may be, in the 95 form shown more particularly in Fig. 2, wherein *d'* indicates a loop-shaped foot, *d*² a vertical shank, and *d*³ a laterally extending arm at the upper extremity of the hanger, said hanger being provided on the shank *d*² with arms *d*⁴ operating mainly as 100 a gage to denote the level of the water in the tub.

The hangers are attached to and supported by saddles E, the latter being positioned on the top edges of the tub at the opposite side walls thereof. Each saddle is a substantially U-shaped casting adapted to be placed in a vertical position over the top edge of the tub, one leg of the saddle being in contact with the inner surface of the 110

2

tub and the outer leg of the saddle being provided with a threaded aperture which receives a binding screw δ . After the saddles are placed in position on the walls of the tub the binding screws are adjusted to clamp the saddles immovably in position, but, obviously, the screws may be released and the saddles detached from the tub. The arms d^3 at the upper ends of the hangers 5 D D' extend outwardly and rest upon the saddles E, whereby the weight of the hangers and the loaded cylinder A is impressed directly upon the saddles. The hangers are attached to the saddles by means of bolts f having thumb nuts f' . As shown in Fig. 3, the arm d^3 of hanger D is provided with slots j^2 through which the bolts f pass, thus providing for a limited adjustment of the hanger relative to the saddle. This adjustment is for the purpose mainly of positioning the hangers within the tub so as to be free from contact with the side walls thereof, it being found in practice that it is common to install tubs some of which have 10 downwardly converging walls and others have vertical walls. The attachment of the hangers to the saddles is for the purpose mainly of securing the slight adjustment necessary to enable the hangers for use 15 in tubs which have either inclined or vertical walls. Obviously, the adjustment of the hangers on the saddles may be obtained by the use of slightly enlarged holes instead of the slots, but as this is an expedient well known to mechanics, I have not considered it necessary to illustrate the same herein.

One of the saddles carries a base plate F for supporting a motor G and the gearing, the latter forming an automatic reversing 20 drive between cylinder A and motor G. The motor may be of any suitable kind, but in the drawings I have illustrated an electric motor the armature shaft g of which rotates continuously in one direction. This motor is mounted on a suitable bed g' , the latter being fastened in any suitable way to the bed plate F attached to one of the hangers. The bed plate g' is provided with an upstanding yoke-shaped bearing h in which is journaled a vertically positioned counter-shaft H, the upper end of which shaft is furnished with a worm gear h^1 in mesh with a worm g^2 on the armature shaft g . The lower end of said counter-shaft H is provided with 25 a bevel gear h^2 , the latter operating to impart motion to bevel gears J J'.

K designates a cylinder driving shaft positioned horizontally above the bed plate g' and journaled in suitable bearings provided 30 on the posts k thereon, said shaft K being in the vertical plane of the countershaft H, which I have termed the driving shaft and directly below it. At one end the driven shaft K is provided with a gear k^1 which meshes directly with a large gear k^2 secured on the

drum shaft C, (see Fig. 1) whereby shaft K operates as a means for imparting movement to drum A through the intermeshing gears k^1 k^2 . The bevel gears I J are mounted loosely on the shaft K so that the shaft will 35 rotate within said gears, but one gear or the other is adapted to be made fast with shaft K by a clutch L. Said clutch is positioned on the shaft K intermediate the gears I J, (see Fig. 4), and the clutch is connected by 40 a spline I with the shaft in order that it may be shifted thereon and still be connected thereto, so that the clutch will rotate at all times with the shaft. The gear I is provided with a clutch pin i ; similarly the 45 other gear J is provided with a clutch pin j . The clutch L is provided with clutch pins m m' or with a series of such clutch pins. As shown, the clutch pin m extends from one face of the clutch so that the pin i on gear 50 I is in the path of said pin m . The other clutch pin m' of the gear extends from the other face of the clutch in order that it may engage with the clutch pin j on gear J, but the engagement of one clutch pin or other of 55 the clutch with the clutch pin on the corresponding gear depends upon the position of the clutch. It will be noted by reference to Fig. 7, that the clutch pins m m' are yieldably connected thereto, each clutch pin being shown as having a sliding engagement with the body of the clutch, and, furthermore, each clutch pin is backed by a coiled spring m^2 which is housed within a socket or chamber provided in the body of the clutch. The sliding engagement of the pins 60 m , m' , may be effected by providing an angular head m^3 for the pins to ride in an angular recess, which recess also serves to house the springs m^2 . If desired, the contacting ends m^1 of the pins m , m' may be beveled, as shown in Fig. 7, and the pins i , j , may also be provided with a beveled contacting surface i^2 , j^2 to coincide with the beveled surfaces of the spring actuated pins m , m' . The utility of the yielding clutch pins will hereinafter appear.

The clutch L is provided with an annular groove n in which loosely fits the forked end n' of a slipper arm N, the latter being attached rigidly to a horizontal slipper rod O. Said rod is slidable in suitable posts o' fixed to the bed plate g' , and, furthermore, said rod is provided intermediate its ends with a yoke O'. Within this yoke are 70 mounted anti-friction rollers p , between which operates a cam P, the edge portion of which is adapted for contact with the rollers, whereby the rotation of the cam imparts reciprocating movement at suitable intervals 75 to the slipper rod O. The cam is carried by a shaft P' supported in a short post q on the bed plate g' , said shaft being provided with a worm gear P^2 which meshes with a worm Q' on an end portion of the cylinder 80

driving shaft K. The worm Q is held rigidly on the shaft in a suitable way, as for example by the binding screw q', but by turning this screw backward the worm can be slipped off the shaft, thus throwing out of action the automatic shifting mechanism for the clutch.

The operation is as follows:—The shaft C of the load-carrying or drum A is positioned 10 in the opening d of the hangers so as to connect the drum to the hangers. The saddles E having been placed in position upon the tub and clamped thereon by the screws the operator now places the hangers and the 15 drum within the tub, thus bringing the arm d² of the hangers into engagement with the saddles, whereupon the bolts f are applied in order to fasten the hangers rigidly to the saddles. The motor and the reversible driving gear are supported on one of the saddles by the plate F, the shaft K being geared to the cylinder shaft. With the clutch L in a position intermediate the two gears I J, the 20 motor G will operate to drive the shaft H and both gears I J, but in the described position of the clutch power is not communicated to the drum. The clothes having been deposited in the drum and the necessary water supplied to the tub, the machine is in condition 25 for operation. The clutch L is shifted in one direction, as to the left in Fig. 4, so the pin m is in engagement with the pin i of gear I, whereupon the motor drives through the gear I and clutch L to communicate motion to shaft K and thus turn the cylinder in one direction. This rotation is continued until such time as the worm Q turns shaft P' and cam P for the cam to impart movement to the shipper rod O and 30 thus disengage the pin m of the clutch from the pin i of the gear I, whereupon the clutch is shifted so that its pin m' engages with pin j of gear J, whereby the motor drives through the gear J and the clutch L so as 35 to reverse the direction of rotation of the shaft, whereby the cylinder will be rotated in an opposite direction. It will be noted that when the clutch is disengaged from one gear the cylinder continues to turn and when 40 the clutch engages with the other gear the acquired momentum of the cylinder has a tendency to wedge or bind the parts so tightly together as to offer undue resistance to the motor. This objection is overcome 45 in my invention by providing the yielding clutch pins m, m' on the shiftable clutch member. Should the acquired momentum of the cylinder have a tendency to cause undue binding or tight frictional 50 engagement of the parts the yielding clutch pin m or m' of the clutch member will slide into its chamber and move past the fixed clutch pin on the gear by reason 55 of the beveled face m⁴ of the spring actuated pins m or m' riding over the beveled 60

faces i² or j² of the fixed pins i or j, thus allowing the cylinder to expend its momentum before the clutch pin of the clutch member will again be brought into position for contact with the fixed clutch pin on the gear, 70 and this takes place when the clutch is shifted in one direction or the other.

It will be noted from the foregoing description taken in connection with the drawings that the load-carrier or cylinder is automatically rotated in one direction for a predetermined length of time and thereafter said load-carrier or cylinder is rotated for another predetermined length of time and in an opposite direction. This reversal in 80 the direction of rotation of the load-carrier or cylinder tends to tumble the clothes within the cylinder and to prevent them from massing to such an extent as to preclude the flow of soapy water through the cylinder, 85 the described operation facilitates the washing of the clothes and reducing the time required.

The entire appliance may be easily and quickly positioned on a tub and as readily 90 dismounted therefrom. The cylinder is made in sizes to suit different tubs, for the reason that I do not find it desirable to employ a cylinder of one size to fit tubs of different dimensions.

In Fig. 8 the cylinder is shown as being provided with an extension hub whereby a cylinder of a predetermined length may be supported within tubs the length of which may vary from one to three inches or more. 100 At one end, the cylinder should be provided with a journal (not shown), but at the opposite end it is provided with an extension journal, so called. Such journal comprises a sleeve R, a spindle R' and an adjusting 105 nut r. The sleeve is flanged at r' and attached firmly to the cylinder, on the interior thereof. This sleeve is internally threaded, and within it is screwed a threaded part of the spindle R', the latter being plain or 110 unthreaded for a part of its length. The nut is screwed on the threaded part of the spindle and abuts against the head of the cylinder. The cylinder is supported in the 115 hangers by the journal at one end and the spindle at the other end, a cotter pin r² being passed through the spindle to retain it in position. Should it happen that the 120 hangers are spaced too far apart by reason of the tub being larger than the cylinder and its journals, then the nut r is rotated to turn the spindle in the sleeve until the spindle is extended the required distance to make up the difference, thus enabling one 125 size of cylinder to be used in tubs of different sizes.

Having thus fully described the invention, what I claim as new, and desire to secure by Letters Patent is:

1. In a reversible drive mechanism, the 130

- combination with a power shaft, and a driven shaft adapted to impart motion to a part to be driven, of reversible mechanism positioned intermediate said power shaft and the driven shaft, said reversible mechanism embodying a plurality of gears mounted loosely on the driven shaft, said gears being positioned in facing relation to each other and provided on their opposing faces with clutch pins, a clutch member splined to the driven shaft and positioned intermediate said facing gears, said clutch member being provided with yieldable clutch pins in the path of which are positioned the clutch pins of said facing gears, means for operating the clutch member at intervals so as to disengage it from one gear and make it fast with the other gear alternately, and means operated by the power shaft for driving said gears, said clutch pins of the clutch member being yieldable to contact with a clutch pin of one gear or the other under acquired momentum of the part to be driven transmitted through the driven shaft.
2. In a reversible drive mechanism, the combination with a power shaft, and a driven shaft adapted to impart motion to a part to be driven, of a plurality of gears mounted loosely on said driven shaft, said gears being in facing relation, a clutch member splined to the driven shaft and positioned intermediate said facing gears so as to be made fast with either gear, means for driving said gears, a shipper rod slidably supported adjacent to the driven shaft is provided with a yoke having spaced anti-friction rollers, means connecting said shipper rod with the clutch member for imparting sliding movement to the latter, a shaft mounted separately from the driven shaft, a cam rotatable with said separately mounted shaft, said cam being positioned within the yoke and between the rollers of the shipper rod and operating to impart reciprocating movement thereto, a worm on the driven shaft, and a worm gear on the separately mounted shaft whereby the worm and worm gear co-operate in driving the separately mounted shaft from the driven shaft.
3. In a reversible drive mechanism, the combination with a power shaft, and a driven shaft adapted to impart motion to a part to be driven, of a plurality of gears loose on the driven shaft, a clutch member splined on the driven shaft and positioned intermediate said gears, means for driving the gears, clutching means on the gears and clutching means on opposite sides of the clutch member to alternately engage the gears for coupling said clutch member to one gear or the other according as the driven shaft is to be rotated in one direction or the other, said clutching means of the clutch member being axially yieldable to acquire momentum of the part to be driven transmitted through the driven shaft for precluding undue frictional contact by causing slip at the moment of engagement between the clutch member and one of said gears.
4. In a reversible drive mechanism, the combination with a driving gear, a driven shaft having spaced driven gears loosely mounted thereon and meshing with the driving gear, clutch pins on the driven gears, a clutch member splined on the driven shaft and having yieldable pins to coact with the pins of the driven gears, mechanism for reciprocating the clutch member to alternately engage the clutch pins, and means on the driven shaft for actuating said mechanism.
5. In a reversible drive mechanism, the combination with a driving gear, a driven shaft having spaced driven gears loosely mounted thereon and meshing with the driving gear, clutch pins on the driven gears, a clutch member splined on the driven shaft and having yieldable pins to coact with the pins of the driven gears, a shipper rod connected with said clutch member and provided with a yoke, a cam mounted for movement in said yoke to shift the shipper rod and clutch member, and means rotatable by the driven shaft for imparting movement to said cam.

In testimony whereof I have signed my name to this specification in the presence of two subscribing witnesses.

JOHN W. CAVANAGH.
